UNITED STATES PATENT OFFICE.

THEODOR WENSEL, OF ST. PAUL, MINNESOTA.

PRINTER'S HOOK.

No. 843,648.

Specification of Letters Patent.

Patented Feb. 12, 1907.

Application filed July 16, 1906. Serial No. 326,371.

To all whom it may concern:

Be it known that I, THEODOR WENSEL, a citizen of the United States, residing at St. Paul, in the county of Ramsey and State of Minnesota, have invented a new and useful Improvement in Printers' Hooks, of which the following is a specification.

My invention relates to locking devices commonly called "printers' hooks" or "clamps" for stereotype and other plates.

My principal object is to provide a simple and efficient printer's hook; and the invention consists, further, in the construction and combination of the clamp-jaw, block, and screw illustrated in the drawings and herein-after described and claimed.

In the drawings, Figure 1 is a view of my hook from above. Fig. 2 is a side view. Fig. 3 is a front view. Fig. 4 is a central longitudinal section. Fig. 5 is a front view of the head of the screw. Fig. 6 is a longitudinal plan of the screw. Fig. 7 is a plan of the clamp-jaw, and Fig. 8 is a side view of the clamp-jaw.

My device comprises, essentially, three parts: first, a clamp-jaw 1, provided with the hook 2; second, a block 3, formed with a centrally-threaded cavity 4 of uniform diameter and pitch, which passes through the entire length of the block, said block also having slots 5, parallel with said cavity 4, located substantially midway between the top and bottom of the block; and, third, a screw both ends 6 and 7 of which are uniform in diameter and pitch, said diameter and pitch corresponding with those of the central cavity 4 in the block. The ends 6 and 7 of the screw are connected by a shaft 8 of relatively small diameter.

The shaft of the screw is adapted to pass through and have its bearing in a yoke-opening 9 in the clamping-jaw, the latter being formed with side flanges 10 and 11. The flange 10 is adapted to slide in the slots 5 of the block, while the flange 11, carrying the hook 2, moves upon the upper bearing-surfaces 12, which are formed on the top of the block. The screw is threaded into the central cavity of the block, and its construction as described is such that its end 6 will follow through the entire length of the central cavity of the block, and as this movement carries with it the clamping-jaw wide adjustability of the hook upon the plates is possible. The coaction between the slotted block and flanged clamping-jaw also secures

accuracy of movement and rigidity of the hook when clamped upon a plate. The head of the screw is crossed by a plurality of slots 13, while portions of the upper surfaces 14 and 15 of the block immediately adjacent to the screw are beveled to permit the manipulation of the screw from above when its head has receded so that it is not readily accessible from in front—that is to say, this slotting of the screw and beveling of the upper surface of the blocks enables the operator in locking or unlocking a plate to turn the screw from in front or above, as is most convenient.

The operation of my device is obvious. As is usual a series of the clamps are used for fastening and adjusting a plate in a chase, the edges of the plate being locked between the hooks 2 of the clamp-jaws. The screw is actuated by inserting a tool in the slotted head, and as the screw is turned it carries with it the clamp-jaw, which is yoked upon the shaft of the screw by means of the opening 9 in the clamp-jaw. Thus by the manipulation of the screw-head the plate may be gripped or released at the will of the operator.

Having described my invention, what I claim as new, and desire to protect by Letters Patent, is—

1. A printer's hook, comprising a block, clamping-jaw and screw, said block containing a central cavity and two longitudinal slots extending from the central cavity to the outer surfaces of the block and said jaw being provided with lateral flanges respectively adapted to slide in and above said slots.

2. A printer's hook comprising a block, clamping-jaw and screw, said block containing two longitudinal slots extending transversely to its outer surfaces and substantially midway between its upper and lower surfaces and a central, threaded cavity of uniform diameter adapted to receive the screw while said jaw is provided with lateral flanges respectively adapted to slide in and above said slots.

3. A printer's hook comprising a block, clamping-jaw and screw, said block containing two longitudinal slots and a central, threaded cavity of uniform diameter, parallel with said slots, said jaw, being provided with lateral flanges adapted to slide in said slots and a yoke for said screw, formed to fit over the central portion thereof, while both ends of the screw are threaded in the central cavity of the block.

4. A printer's hook comprising a block

formed with a central threaded cavity, a screw having an intermediate shaft and threaded ends adapted to fit, and move through, said threaded cavity, and a clamping-jaw provided with a yoke adapted to span said shaft and connect the jaw with the screw.

5. A printer's hook comprising a block, clamping-jaw and screw, said block containing two longitudinal slots and a central, threaded cavity of uniform diameter, parallel with said slots, said jaw, being provided with lateral flanges adapted to slide in said slots

and a yoke for said screw formed to fit over the central portion thereof, while both ends of the screw are threaded in the central cavity of the block, whereby the screw in said cavity is adapted to follow the jaw as it moves the length of the block.

In testimony whereof I have signed my name to this specification in the presence of two subscribing witnesses.

THEODOR WENSEL.
